UNITED STATES PATENT OFFICE.

FRANCIS GLANVILLE INGLIS, OF LINTHORPE, MIDDLESBROUGH, ENGLAND.

APPARATUS FOR COOLING AND PURIFYING GASES.

Application filed April 25, 1927, Serial No. 186,455, and in Great Britain July 21, 1926.

This invention relates to apparatus for the cooling and purifying or treatment of gases by fluids and particularly to that type using liquid for the cooling and purifying medium 5 in which the gas is passed through a series of perforated members, alternatively fixed and revolving, and wherein the cooling and purifying liquid is introduced and is broken up into small particles by the revolving members 10 and thereby intimately mixed with the gas; the particles of dust or dirt in the gas are thereby saturated and entrained in the water which is thrown outwardly by centrifugal force, whilst the gas is drawn 15 through the perforated members by a fan or other known means provided for the purpose.

The present invention comprises apparatus for cooling, purifying or treating gases, consisting of one or more pairs of perforated 20 discs of which one member of each pair is fixed while the other rotates, the gases being forced or drawn through the perforations in the discs so as to be intercepted by transversely moving streams of liquid passing 25 radially between the discs. One or both of the adjacent surfaces of each pair of discs between which the liquid passes is or are provided with projections arranged to break up the liquid.

30 A manner of carrying out the invention is illustrated by the accompanying drawings wherein Figure 1 is a partly sectional elevation of a gas washing device made in accordance with the present invention, Figure 2 a 35 side elevation of Figure 1, Figure 3 an enlarged view of the main details of the apparatus, Figure 4 is an alternative construction of the main details shown in Figure 3, Figures 5 and 6 are front and side elevations of a 40 modified construction of one of the discs and Figure 7 a modification of Figure 5.

In these drawings 2, and 3, 2^a and 3^a, 2^b and 3^b are three pairs of perforated discs, 4 being the perforations in the discs. The discs 2, 2^a 45 and 2^b, are fixed to a hollow annular member 5 secured in a main casing 6 of the apparatus, while the discs 3, 3^a and 3^b are fixed on a rotary drum 7 fixed on a driving shaft 8 and of which the outer end is open, while the 50 inner end is formed as an extension of the boss 9 of a centrifugal fan having blades 10 so that the fan is rotated simultaneously with the discs 3, 3^a and 3^b.

All the discs have central holes and the 55 drum 7 is of step like or conical formation to take the discs 3, 3^a and 3^b which are of gradu-

ally increasing size, the annular member 5 being similarly stepped to receive the fixed plates 2, 2^a and 2^b. The drum 7 is provided with a series of perforations 11 so arranged that as the drum 7 rotates these perforations come one after the other immediately in register with a number of fixed jet nozzles 12 through which is forced washing water or other liquid with which the gases are to be treated. The fixed pipes 12^a of the jet nozzles 12 extend into the open end of the drum 7 and the nozzles are arranged to deliver radial jets towards the openings 11 in the drum 7. The annular member 5 is provided with a diametrically opposite series of perforations 13 which convey the water after it has treated the gases to a waste water pipe 14 which extends downwards into a reservoir in which the water is kept at a level 15 to form a water seal over the end of the pipe 14.

On the adjacent surfaces of the pairs of discs 2 and 3, 2^a and 3^a, 2^b and 3^b are provided a suitably spaced series of projections 16, those on the fixed discs being arranged at radial distances from those on the rotating discs. The projections on the discs may be placed thereon as shown in Figures 1 and 3, or radiating from the centre as shown on the revolving discs in Figure 4; or they may be 85 placed at any intermediate angle as may be found most suitable.

The projections 16 are shown inclined away from the axis of the shaft, they may however, be of any other suitable shape adapted to 90 break up the jets of water passing between the discs.

The gases enter the casing 6 through the inlet 19 and are drawn through the perforations 4 of the discs by the blades 10 of the fan 95 and discharged from the casing 6 through an outlet 20.

The series of pairs of discs, 2 and 3, 2^a and 3^a, 2^b and 3^b are duplicated on the other side of the fan, there being a corresponding inlet 19^a to this duplicate series of pairs of discs. A discharge outlet 14^a is provided for the washing water, the gas discharge outlet 20 being common to the series of discs on both sides of the fan. The gas outlet 20 is provided with a drain pipe 21 extending into the same reservoir as the pipes 14 and 14^a.

In the modification illustrated by Figures 5 and 6, the discs 2, 3, etc., are constructed with a number of uniformly disposed openings 25 in each of which is fixed a meshing 110 26 formed by interlaced bars or wires.

In the further modification illustrated by Figure 7, each opening 25 in the discs 2, 3, etc. is covered by meshing 26 held over the opening 25 by bolts 27.

5 By means of the above apparatus the gas and water are brought into thorough and intimate contact during the rotation of the fan by the shaft 8, the apparatus being in a manner similar to a turbine, the fixed discs, 2, 2^a and 2^b being the stator element while the rotary discs 3, 3^a and 3^b are the rotary element, and the projections 16 the blades of the turbine.

10 The discs 2 and 3, 2^a and 3^a, 2^b and 3^b are shown with projections 16 on one side only, they may however be provided on both sides and a corresponding additional system of jets and openings provided as shown in Figure 4. While the discs are rotating the liquid from 15 the jets 12 received by the inner series of rotating projections 16 is thrown by centrifugal force on to the projections 16 of the fixed discs where it is broken up and rebounds on to the next set of rotating projections 16, and 20 so on gradually working from the centre outwards until it passes away through the holes 13.

25 As the successive pairs of discs are each provided with clean water jets, the partly cleaned gas from the perforations 4 of the first pair is subjected to a second cleaning while passing through the perforations of the second pair of discs and so on through the third pair of discs, thereby effecting a most 30 thorough and effective purification of the gases under treatment.

35 The discs may be made in the form of plates with holes drilled or punched therein and with projections bolted or otherwise secured thereto, or they may have the holes and projections pressed out, or otherwise integrally formed. The discs may if desired consist of interlaced bars forming a meshing, as 40 has already been proposed in other washers.

45 The fixed discs 2, 2^a and 2^b are secured to a separate ring 5, so disposed that it can be moved within limits in a direction parallel to the centre shaft, by means of screws and nuts 6^a and 6^b, by which means the discs secured thereto may be placed at any desired 50 distance from the revolving discs, and the intensive washing action of the apparatus increased or decreased without dismantling.

55 The apparatus may be constructed with one pair of discs where a high degree of cleaning is not desired, and any number of subsequent pairs of discs may be added to suit the degree of cleaning desired.

Instead of constructing the apparatus

60 within the casing of a centrifugal fan it may be constructed within a self-contained chamber, and the gas be either forced or drawn through the discs by any known means.

65 What I claim and desire to secure by Letters Patent is:—

1. Apparatus for treating gases comprising a series of fixed annular perforated discs, a series of rotary annular perforated discs, a series of fixed radial liquid jet nozzles, a casing in which the fixed discs are secured 70 and means for drawing the gases through the perforations in the discs, a rotary stepped drum, the rotary discs being fixed on the steps of the drum, and the rotary drum provided with openings in its periphery arranged over 75 the fixed radial liquid jet nozzles.

2. Apparatus for treating gases comprising a series of fixed annular perforated discs, a series of rotary annular perforated discs, a series of fixed radial liquid jet nozzles, an 80 outlet for the liquid from the nozzles, a casing in which the fixed discs are secured and means for drawing the gases through the perforations in the discs, the radial nozzles being arranged to operate between the annular discs 85 from their inner peripheries and fixed relatively to both the rotary and fixed discs, and the casing aforesaid having therein radial holes between the fixed discs leading to the jet liquid outlet.

90 3. Apparatus for treating gases comprising a series of fixed annular perforated discs, a series of rotary annular perforated discs, a series of fixed radial liquid jet nozzles, a casing, an adjustable ring, and means for 95 drawing the gases through the perforations in the discs, the radial jet nozzles being arranged to operate between the discs and fixed relatively to both the rotary and fixed discs and independently of any of the rotary parts 100 of the apparatus, and the fixed discs secured on the adjustable ring which is adjustably fixed in the casing.

105 4. Apparatus for treating gases comprising a series of fixed annular perforated discs, a series of rotary annular perforated discs, a series of fixed radial liquid jet nozzles, a casing, a stepped ring, and means for drawing the gases through the perforations in the discs, a rotary stepped drum, the rotary discs 110 being fixed on the steps of the drum, and the rotary drum provided with openings in its periphery arranged over the fixed radial liquid jet nozzles, the fixed discs being secured to the steps on the ring, the ring being supported in the casing.

115 In witness whereof I affix my signature.
FRANCIS GLANVILLE INGLIS.
